MEANS FOR EXTRACTING WATER FROM
WEBS OF PULP OR PAPER

William Parsonage Evans, Swinton, England

Application June 26, 1934, Serial No. 732,426
In Great Britain June 26, 1933

6 Claims. (Cl. 92—52)

These improvements are concerned with paper-making machines, or machines for drying paper, fabrics, or it might be other materials, but they relate primarily to an improved method of 5 and means for extracting water from the paper web carried upon the "wire" in paper-making machines, and whereby I am enabled to obtain a better drying effect in a simple manner and with less wear and tear upon the "wire" and 10 other parts.

It is known to support the "wire" in paper making machines upon endless laterally corrugated belts and to extract the water by side suction devices across the mouths of which the edges 15 of the endless laterally corrugated belts travel. It is also known to use a laterally corrugated endless belt to support the "wire", and to close the corrugations at the extremities by endless moving side bands, the laterally corrugated endless belt co-operating with an open topped suction box or boxes in which a further endless band 20 operates, there being a series of holes in the laterally corrugated endless belt leading into the suction box or boxes. In such schemes, as the latter, where holes in the laterally corrugated belt led to the suction box, considerable disadvantages followed, in so much, that a liquid seal 25 was requisite to the open topped suction box, a number of endless bands were required, and the atmospheric pressure upon the endless laterally 30 corrugated belt was considerable and extended over the entire area passing over the open topped suction box or boxes, and which was necessarily a very appreciable area.

An open topped suction box the full width of the endless belt is subjected to considerable atmospheric pressure over the functioning area, whilst with smaller open-topped suction boxes 35 the drainage holes in the corrugated endless belt are local in effect to the size of suction box and can only be effective over a limited area. Likewise the smaller open topped suction boxes do not afford adequate support to the travelling corrugated endless belt.

My invention has to do with an improved method and means which mark a considerable advance in the state of the art, in so much that I follow an improved method and means which 40 overcome the difficulties hitherto encountered, in trying to effectively drain water from a paper web or the like carried on a "wire" supported by an endless belt which is adapted to be drained.

According to my improved method of extracting water from the paper web supported on the 45 "wire" in paper machines, and for like water ex-

tracting purposes, use is made of a substantially closed suction box structure approximately the width of the web and this has spaced lateral apertures and there co-operates therewith one endless belt having lateral channels, belt drainage holes, and solid selvedges, and the improved method is distinguished by this, that, said belt and what it supports is only subjected to atmospheric pressure immediately over those narrow areas where the belt drainage holes pass over 5 the apertures in the substantially closed surface of the suction box structure. Further the top of the suction box structure, being a substantially flat and closed surface, it affords admirable support to the under face of the one endless belt, 10 and difficulties of sealing of belt to the suction box structure are overcome. Further, the substantially flat belt supporting face of the substantially closed-in suction box is perforated, or it might be ribbed, to permit air to pass over areas 15 between belt and suction box structure, and the suction box structure may be fashioned as to its 20 upper surface to assist the getting rid of silt.

Also the substantially closed suction box structure enables me to conduct the paper web, wire, 25 and endless revolvable belt in substantially a uniform plane and to resist any tendency to sag into the known open-topped suction box over an appreciable area, which is an obvious drawback 30 entailing considerable power to effect driving and resulting in much wear and tear.

The means which enable me to operate according to the improved method, include a single endless belt with blank or solid selvedges which close the lateral channels, and a practically flat suction box structure in one or more parts and substantially closed save for the lateral apertures, slots, or holes, and which suction box structure affords adequate support to the 35 said single endless belt which only requires to submit to atmospheric pressure over very narrow and well distributed lateral areas.

The improvements are illustrated in the accompanying drawings, wherein:—

Fig. 1 is a broken end elevation showing a typical example of the improvements in connection with the "wire" of a paper making machine.

Fig. 2 shows a plan of Fig. 1 and clearly indicates the one endless belt broken away, and also one construction of the substantially closed 50 suction box structure.

Fig. 3 is a section of the belt and suction box structure on the line 1—1, Fig. 2.

Fig. 4 shows a similar section on the line 2—2, Fig. 2.

Fig. 5 indicates a portion of a modified endless belt with solid, blank, or closed selvedges, and in which the channels, which are there shown in plan, are sinuous.

5 Figs. 6 and 7 are views which show that deckle straps adjustably carried may be used to limit the effective width of the one endless support belt.

10 Fig. 8 is a sectional view showing the suction box structure and the endless revolvable channelled belt in several modified forms.

Fig. 9 is a section of a modified revolvable support belt taken on the line 3—3, Fig. 8.

15 Fig. 10 is a section of a modified revolvable support belt taken on the line 4—4, Fig. 8.

Fig. 11 is a plan of the suction box structure.

The improvements are illustrated by the Figs. 1 and 2 as applied in connection with the "wire" of a paper making machine, which "wire" is marked *a*, and this "wire" in addition to passing over the known sustaining means receives support from a single revolvable endless belt such as *b*. This belt may be made from any suitable material or materials, as for instance it may be 25 a rubber or rubber-covered belt, but in any case is fashioned with channels such as *b'* which are close-pitched and have a lateral disposition. The channels may be straight or sinuous, as indicated by the Fig. 2 and Fig. 5. These channels *b'* 30 have belt draining holes *b²* which are widely arranged laterally of the belt but extend, in pitched relationship, across the full width of the belt. The belt has a solid, blank, or closed selvedge *b³* along each edge, that is, the channels *b'* do not 35 extend the full width of the belt so that water passing into the channels *b'* can only drain through the aligned and spaced drainage holes *b²*.

The endless belt *b* is carried upon support rollers *c*, *c*, which may be free to revolve, or it may 40 be driven and there may be means for tensioning the endless belt *b*. Also means for checking undue lateral movement of said belt, as indicated in Fig. 2, and for delivering water to the extreme edges of the belt, such as is illustrated in Fig. 1.

45 The upper run of the belt *b* passes over a co-operating suction box *d*, which is well shown in Figs. 1, 2 and 11. This suction box *d* has a substantially flat upper face or top, across which the endless belt *b* travels, the under face of the 50 upper stretch of the belt contacting therewith. Said suction box is substantially a closed vessel, save for lateral apertures or slots *d²* at pitched or spaced intervals across the full width of said suction box and which slots *d²* coincide with the

55 belt drainage holes *b⁴*; or alternatively, I may provide a series of holes *d^{2x}* (see Figs. 8 and 11). The suction box *d* is exhausted through the pipes *d³*, *d³*, which lead into a common pipe *d⁴* upon which the pump or the like acts, and the suction 60 from the pump thus serves to produce a suction effect upon the several sets of the lateral apertures or slots *d²* or the holes *d^{2x}*. As a consequence, water from the "wire" *a* enters the channels *b'*, and is well and evenly distributed 65 over the width of the belt, and, as the belt drainage holes *b²* pass over the lateral slots *d²* or holes *d^{2x}*, so the water is sucked into the substantially closed suction box and drained out along the pipes *d³*, *d³* and *d⁴*. If Figs. 4 and 8 are examined,

70 it will be seen, how the water is drawn from the channels *b'* in the endless travelling belt *b*. It will be also be seen that suction is only exercised upon the well and proportionately distributed areas represented by the spaced lateral slots *d²* 75 or holes *d^{2x}*, and consequently the "wire" and

belt have not to reckon with the very considerable atmospheric pressure at all times thrown onto considerable areas of the "wire" and supporting belts in known schemes. In the formerly known schemes the result of atmospheric pressure on the main belt supporting the "wire" and web to be drained made it extremely difficult to drive the belt. Further with my proportionately distributed linable drainage holes *b²* moving over the narrow and correspondingly spaced lateral 10 apertures, slots, or holes, in the otherwise closed suction box structure there results a better distributed drainage effect with lessened liability for local water accumulation to occur.

15 In order to prevent trapping of air or to facilitate the passage of air between the endless belt *b* and substantially closed suction box *d*, a series of holes *f* are provided through the upper wall of said suction box *d* over which the one endless belt travels. Also, to get rid of "silt", or the like, 20 below the said endless belt *b* I may provide other apertures *e* which serve to scrape away such silt and permit same to travel through and to fall clear of the suction box structure *d* (see Figs. 2 and 3).

25 The solid, blank, or closed selvedges *b³* define the limits of the channels *b'*, and the belt drainage holes *b²* come in succession into register with the lateral slots *d²* or holes *d^{2x}*, as the belt *b* and wire *a* travel over the top of the substantially closed suction box *d*, and so one belt and a supporting suction box structure (closed save where the spaced ranks of belt drainage holes *b²* register) suffices for the service required.

30 In Figs. 6 and 7 I show the use of deckle strap *h*. 35 These are intended to be adjusted laterally across the endless travelling belt *b* with solid, blank, or closed selvedges, to suit the width of paper intended to be produced.

The Figs. 8, 9 and 10 suggest slight variations 40 in the structure of the belt *b*. According to the Fig. 9 and left-hand portion of Fig. 8 on the line 3—3, the upper face of the belt has a covering *b⁴* of pervious or open cotton felt or wire gauze, or both, in addition to the grooves *b'* and belt drainage outlet holes *b²*, the belt necessarily having solid selvedges *b³*. In Fig. 10 and the right-hand half of Fig. 8 on the line 4—4, the belt has a complete layer or thickness of pervious or open cotton felt or the like *b⁵*, the edge strips or lengths 50 *b⁶* of which are treated with rubber and firmly adhered to the selvedges of the belt *b*. In both these examples the grooves *b'* laterally of the endless belt *b* have drainage holes *b²*.

An important feature of my method is that 55 the suction box is in effect a continuous closed structure over which the one belt passes and which belt is only subjected to atmospheric pressure over well distributed comparatively very narrow lateral areas, and that with the air relief 60 holes *f* and silt removal apertures *e* in the upper wall of the suction box there is no tendency to set up any vacuum effect between the inside face of the belt and the support face of the suction box structure such as would seriously resist the 65 travel of the belt, and, as a consequence, it is an easy matter to drive the one belt even by the forwarding action of the "wire".

I may provide slightly projecting ribs on the support face of the suction box structure *d* as is indicated at one place by the dotted lines at *r* in Fig. 11 to allow air to get between the belt and the face of the suction box.

75 A series of substantially closed suction box structures and belts as described may succeed

each other in one machine, and the suction effect may vary as between the several substantially closed suction boxes.

I claim:

5. 1. Means for carrying out the improved method of extracting water from paper webs, comprising an endless flexible revolvable belt, laterally extending channels therein having drainage holes and closed selvedges, all inherent in said belt, said belt being adapted to support the wire and web, a suction box wherewith the belt cooperates and having laterally spaced apertures in its upper surface but being otherwise closed, means to admit air between said belt and said suction box 10 structure, and revolvable means to support the belt, all whereby the disadvantages of unbalanced atmospheric pressure is overcome and the suction effect on the belt and what it supports only occurs where the belt passes over the lateral apertures in the suction box for the purposes stated.

2. Means for carrying out the improved method of extracting water from paper webs, comprising an endless flexible revolvable belt structure with 15 laterally extending channels therein having drainage holes, said belt having solid selvedges and adapted to support the wire and web, and a suction box structure with laterally spaced apertures over which the belt rides, said suction box 20 structure being otherwise closed, and provision to admit air below said endless flexible revolving belt structure and the top of said otherwise closed suction box structures, for the purposes related.

3. In a paper making machine of the Four-drinder type, a suction box having alternate channels and ribs on its upper face, said channels having free communication with the atmosphere and the ribs between the channels having suction ports leading from their upper edges to the interior of the box, and an endless belt for supporting the wire belt of the machine having an upper run resting on said ribs, said endless belt having upstanding flanges at its edges and provided with closely spaced channels extending between said 35 flanges, said channels having suction ports in their bottoms passing successively over the suction ports of the ribs.

4. Means for carrying out the improved method of extracting water from paper webs, or other material, comprising a substantially closed suction box with support face, spaced lateral apertures in said support face, an endless revolvable belt, lateral channels in said belt, closed selvedges 40

to said belt, drainage holes from the channels in said endless revolvable belt, said drainage holes adapted to progressively coincide with the spaced lateral apertures in the support face of said substantially closed suction box, means to permit free access of air between the inner face of the upper stretch of endless revolvable belt and the substantially closed top of the suction box, means to assist removal of silt between said endless revolvable belt and the substantially closed top of the suction box, means for supporting and permitting rotation of said endless revolvable belt and means for draining said substantially closed suction box.

5. Means for effecting extraction or drainage 15 of water from a travelling web of paper or other material supported upon a "wire", or otherwise, and consisting of an endless revolvable belt with lateral channels in said belt, closed selvedges to said belt, drainage holes from the channels in 20 said belt, said drainage holes adapted to coincide with distributed lateral apertures in the support face of a substantially closed suction box, means to permit access of air between the lower face of the endless revolvable belt and the substantially closed top of the suction box, means to assist removal of silt, means to support and permit rotation of said endless revolvable belt, means to supply water to the edges of said belt, and drainage provision to permit suction drainage of 25 30 said substantially closed suction box.

6. Means for effecting extraction or drainage of water from a travelling web of paper or other material supported upon a "wire", or otherwise, comprising a substantially closed suction box 35 structure with support face and lateral apertures in spaced relationship in said support face, a single endless revolvable belt, lateral channels in said belt, closed selvedges closing said channels at the ends, drainage holes in spaced relationship 40 from the channels in said belt adapted to coincide with the lateral apertures in spaced relationship in the support face of the substantially closed suction box structure, outlet holes to permit access of air between the inner face of said 45 endless revolvable belt and top of said substantially closed suction box structure, means to assist removal of silt, rollers to support and permit rotation of said endless belt, means to supply water to the edges of said endless belt, and suction pipe provision to said substantially closed 50 suction box.

WILLIAM PARSONAGE EVANS.
